Des. 211,500

Patented June 18, 1968

211,500

FIN FOR WATER SKIS AND THE LIKE

Walter J. Lauterback, 448 W. Pioneer Drive,
Glendale, Calif. 91203

Filed June 12, 1967, Ser. No. 7,435

Term of patent 14 years

(Cl. D71—1)

FIG. 1 is a perspective view of a fin for water skis embodying my new design;

FIG. 2 is a top view thereof;

FIG. 3 is a side view thereof;

FIG. 4 is a bottom view thereof;

FIG. 5 is a rear view thereof; and

FIG. 6 is a front view thereof.

I claim:

The ornamental design for a fin for water skis and the like, substantially as shown.
